BOX FOR CONTAINING AMMUNITION
Oswald Hoffmann, Lintorf, Bezirk Dusseldorf, Germany
Filed Aug. 5, 1959, Ser. No. 831,836
Claims priority, application Germany Aug. 7, 1958
2 Claims. (Cl. 220—97)

The present invention relates to boxes adapted for example to contain ammunition and which are intended to be stacked. It is an object of the invention to provide the boxes with means whereby when stacked they will not slip.

According to the present invention a box, for example for containing ammunition, has at least two opposed side walls provided with projections or recesses so arranged that when the boxes are stacked, the projections or recesses on the adjacent walls of juxtaposed boxes will make mutual nesting engagement.

In one embodiment the walls are formed with beads for example arranged in curved or rectangular patterns, which stand out in relief and which are appropriately dimensioned and positioned to enable the beads of juxtaposed boxes to make nesting engagement. If desired however the walls may have a series of pip-like projections in place of the beads.

One embodiment of the invention will now be described by way of example by reference to the accompanying drawing, in which

FIG. 1 is a side view of an ammunition box according to one embodiment of the invention,

FIG. 2 is an end elevation, and

FIG. 3 is a plan view.

As shown in the accompanying drawing, an ammunition box consists of the body 1 and a lid 2. Each longer side wall of the body 1 is provided with an outwardly projecting bead 3 arranged in the pattern of a rectangle. The bead 3 on one side wall defines a rectangular pattern of different dimensions to that on the opposed side wall such that when the boxes are stacked, the rectangles on adjacent walls of juxtaposed boxes will make nested engagement and so prevent the boxes in the stack slipping. The extent the beads 3 project is such that, when the boxes are stacked one upon the other on their sides, the lids 2 can be opened from the front. As shown the lid has fixing straps 4 extending across the outer face of the lid, and connected to fixing hooks 5 hinged on the end wall of the box. In order to prevent the fixing straps

2

from projection outwardly of the lid they are located in recesses in the lid.

The beads 3 need not be of rectangular pattern but may define any other geometrical shape such as for example, an ellipse.

If desired one side wall may have a projecting bead of rectangular, elliptical or other pattern and the opposed side wall may have a groove or recess of corresponding shape such that when a series of boxes are stacked, the bead and groove of the side walls of juxtaposed boxes will make nesting engagement.

In an alternative embodiment the opposed side walls are formed with a series of pip like projections, or one side wall may have a series of pip like projections and the other a series of dimple or like shaped recesses such that when the boxes are stacked, the pips on the wall of one box will nest in recesses on the adjacent wall of a juxtaposed box.

I claim:

- 20 1. An ammunition box of rectangular shape comprising a projecting bead in each of its two opposing side walls of the box, the bead on one side being differently arranged to that on the other side so that when the boxes are stacked adjacent to each other the beads on the adjacent walls of the juxtaposed boxes will make mutually nesting engagements and each projecting bead being in the form of a rectangle, a removable lid extending across a wall other than one having the projecting bead, a hook hinged to each end wall, and a fixing strap secured to each hook and extending across the lid, the side beads being of such dimensions that when the boxes are stacked side by side they will be spaced sufficiently by said beads to enable the lids to be removed from the front of the stack.
- 25 2. An ammunition box according to claim 1, in which the lid is formed with a recess for each fixing strap and in which the strap is located to prevent the straps from projecting outwardly from the outer surface of the lid.
- 30 35
